(57) **CLAIM**

The ornamental design for a wheel or wheel cover, as shown and described.

DESCRIPTION

This application contains subject matter related to the following co-pending U.S. design patent application:

Application Ser. No. 29/347,282, filed Nov. 19, 2009.

FIG. 1 is a front view of a wheel or wheel cover according to our design; and,

FIG. 2 is a perspective view thereof.

The broken line showing of the rear of the rim and the bolt holes and center hole in the central hub area is included for the purpose of illustrating environment and forms no part of the claimed design.

1 Claim, 1 Drawing Sheet

FIG. 1

FIG. 2
